E. E. NESS

BATTERY TERMINAL FOR UPRIGHT POSTS

Filed April 14, 1923

INVENTOR
ELLING E. NESS.

BY *Felix O. Laughey*
ATTY.

UNITED STATES PATENT OFFICE.

ELLING EDWARD NESS, OF WETASKIWIN, ALBERTA, CANADA.

BATTERY TERMINAL FOR UPRIGHT POSTS.

Application filed April 14, 1923. Serial No. 632,118.

This invention relates to improvements in battery terminals for upright posts and the objects of the invention are to provide a device of this character that can be adapted 5 to any battery with upright posts and particularly to automobile batteries and whereby a sleeve can be dispensed with.

Further objects are to provide a simple and effective device of this kind which can 10 be readily taken apart and which is hampered by no complicated parts.

With these and other objects in view, the invention consists essentially in the novel construction and arrangement of parts as 15 described in the present specification and illustrated by the accompanying drawings that form part of the same.

Referring to the drawings, in which like characters of reference indicate corresponding parts in each figure,

Figure 1 is a top plan view, showing an embodiment of my invention.

Figure 2 is a vertical section.

Figure 3 is a perspective view of my device fitted to the battery terminal and the upright post.

Figure 4 is a similar view of the device detached.

Figure 5 is a longitudinal section through 30 the device.

In the drawings, A represents the device as a whole adapted to be fitted on the upright post B and comprising, as here illustrated, a clamping member 10 formed with 35 a suitable base 11 and sides 12 extending to form a curved looped portion 13 adapted to fit around the upright post B of a battery.

The sides 12 are provided with openings 40 14 registering with one another and designed to receive therethrough the wire 15 conducting the electric current while the base is provided with a screw-threaded opening 16 adapted to receive therein a clamping screw 17 designed to contact with the upright post 45 B.

In operation, the device, as will be seen in Figure 3, is designed to be clamped into the cable 15 as well as to the post B by means of the single screw 17. This screw 50 is provided with a cap 18 having an opening 19 therein through which a wire nail or otherwise can be inserted to turn the screw.

As shown in Figure 3, the cable carrying the electric current passes through the two 55 holes in the side of the clamping member making a complete circuit.

It should also be noted with regard to the openings 14 that extra holes may also be provided between the screw cap and 60 would be for the purpose of making the device more convenient in certain batteries. For instance, instead of two holes, as shown, another pair, making four holes, could be used as alternatives through which the electric wires may be run.

From the foregoing, it will be seen that I have invented simple, inexpensive and practical means in the form of a battery terminal for upright posts.

As many changes could be made in the above construction and many apparently widely different embodiments of my invention within the scope of the claim, constructed without departing from the spirit 70 or scope thereof, it is intended that all matter contained in the accompanying specification and drawings shall be interpreted as 75 illustrative and not in a limiting sense.

What I claim as my invention is:

A battery terminal structure comprising, in combination, an upright terminal post, a nut threaded on the upper end of the post, a one piece frame presenting spaced side members extending transversely of the post 85 at opposite sides thereof and having their extremities connected by integral transverse portions, said frame being retained on the post by means of said nut and the transverse portions of the frame and being provided with registering slots formed in said side members to provide a passage for inserting a conductor through the frame to lie between the post and one of said transverse portions, said slots being elongated in the 90 longitudinal direction of the frame to permit the latter to move to a position clamping the conductor between the terminal post and the transverse portion of the frame lying at the opposite side of the conductor 95 and means for adjusting said frame to conductor clamping position.

In witness whereof I have hereunto set my hand.

ELLING EDWARD NESS.
